UNITED STATES PATENT OFFICE.

FREDERICK L. SHELOR AND FREDERICK C. SCHOFIELD, OF SALEM, VIRGINIA.

ENGINE-PRIMING DEVICE.

1,300,659.

Specification of Letters Patent. Patented Apr. 15, 1919.

Application filed February 27, 1918. Serial No. 219,352.

To all whom it may concern:

Be it known that we, FREDERICK L. SHELOR and FREDERICK C. SCHOFIELD, citizens of the United States, and residents of Salem, in 5 the county of Roanoke and State of Virginia, have invented certain new and useful Improvements in Engine-Priming Devices, of which the following is a specification.

10 The present invention relates to devices for priming internal combustion engines, and aims to provide a novel and improved contrivance of that nature for effectively priming the engine even under the most 15 adverse weather conditions.

The invention has for its object the provision of a priming device so constructed and operable as to deliver heated vapor or gas to the intake manifold or conduit of 20 the engine when it is started, and thereby enable the engine to start easily and quickly under all conditions.

Another object of the invention is to provide a priming device supplied automatically with gasoline or other fluid, and heated electrically or in an equivalent manner for heating and vaporizing the fluid, so that the vapor or gas in expanding will be injected automatically into the engine intake, 25 such heated vapor or gas mixing with the carbureted air flowing from the carburetor to the engine which will provide a combustible mixture that will start the engine without difficulty, as when the cold carbureted 30 air alone is used.

A further object is the provision of such an engine primer which will not only produce the vapor or gas, but which will also superheat said vapor or gas and keep it in 40 such condition until it enters the intake manifold or conduit. Thus, even though the vapor or gas loses some of its heat to the cooler carbureted air, still the loss of heat will not be sufficient for the vapor or 45 gas to condense, and as a consequence the carbureted air is also heated and in admixing with the heated vapor or gas will produce an effective highly ignitable mixture notwithstanding cold temperatures.

50 A still further object of the invention is the provision of an engine primer having a vaporizing chamber or retort for gasoline or other liquid fuel, electrical or other equivalent means for heating said fuel to vaporize it, and means whereby the vapor will, under a certain pressure flow under pres-

sure to the engine intake when the engine is started, and whereby when the engine has been started and the priming device permitted to cool the fuel will be automatically 60 drawn into said chamber or retort to replenish the supply therein.

The invention has for a further object the provision of a novel construction and arrangement of the parts of the primer, to 65 render it fully efficient and practical.

Another object is to provide a primer which will be operated automatically with the starting device of the engine, so that the priming gas or fluid is delivered under 70 pressure to the engine intake when the starter is operated, the starter furnishing the power while the primer delivers a reliable supply of fuel to assure of prompt starting.

With the foregoing and other objects in 75 view, which will be apparent as the invention is better understood, the invention resides in the construction and arrangement of parts as hereinafter described and claimed, it being understood that changes can be 80 made within the scope of what is claimed, without departing from the spirit of the invention.

The invention is illustrated in the accompanying drawings, wherein—

Figure 1 is a sectional view of the priming device, showing the engine and electrical circuits in diagram.

Fig. 2 is a plan view of a modified form with the top plate removed, portions being 90 broken away.

Fig. 3 is a section on line 3—3 of Fig. 2.

The priming device as illustrated in Fig. 1 embodies a metallic casing 1, of cylindrical or other suitable form and arranged 95 in a vertical or other suitable position. As shown, the casing 1 has a removable cap or end 2 in screw threaded connection therewith, and the casing 1 and its cap 2 each have molded or otherwise provided thereon 100 the exterior insulation 3, thereby preventing them from being grounded by contact with adjacent parts of the engine or frame work of the automobile. The casing 1 also has the lining or interior coating 5 of insulating material of mica, asbestos or other heat and gasoline resisting material, while the exterior insulation 3 may be of hard rubber or composition. The cap 2 has an inner central boss 6 on which is fitted the 105 lower end of a metallic tube 7 arranged concentrically within the casing. Within the

upper end portion of the casing 1 and fitting within the insulating lining 5 is a valve head or body 8 provided with a lower central boss 9 on which the upper end of the tube 7 is 5 fitted. This tube provides the vaporizing chamber or retort therein, and is provided on its exterior and interior surfaces with the jacket or coating 10 and lining or coating 11 of mica, asbestos or other heat and gaso-
10 lene resisting insulation of tubular form. The ends of the tube 7 abut the cap 2 and the valve body 8 and are soldered thereto, as at 12, the insulation of said tube also ex-
tending to said cap and body.
15 In order to electrically heat the interior of the retort or vaporizing chamber an electrode disk 13 is fitted within the insulating lining 11 of the tube 7 at the lower end thereof, and has a stem 14 extending out-
20 wardly through the boss 6 and cap 2 and having a nut 14^a on its protruding portion to provide binding post for the connection of an electrical conductor or leader. Insula-
25 tion 15 is provided under the disk 13 and around the stem 14 to insulate them thor-
oughly from the cap 2 and tube 7. Packing 16 is also provided between the insulation 15 and stem 14 and between said insulation and boss 6 to prevent leakage of the fuel from
30 within the retort or vaporizing chamber. Said chamber is filled or packed tightly with broken pieces of carbon or other equivalent porous electricity-resisting material, or carbon or equivalent pellets can be used, a sec-
35 ond electrode disk 19 being disposed on top of said carbon pack 17. The electrode disks 13 and 19 have the contact points or spurs 18 and 20, respectively, extending into the ends of the carbon pack which is compressed
40 between said disks, thus assuring of good electrical connections for the flow of an elec-
trical current through the pack between the electrodes. The upper electrode disk 19 is forced toward the disk 13 by a strong coil
45 spring 21 disposed between it and the boss 9, so as to compress the carbon pack and enhance the flow of electrical current through same. The pressure spring 21 is also se-
cured to the disk 19 and boss 9 to carry the
50 current therebetween.

The valve body 8 is provided with means for the flow of gasoline or other priming fluid into the vaporizing chamber and the outflow of vapor or gas therefrom, and for 55 these purposes, said body 8 has a passage 22 opening through the boss 9 into said chamber for both the inflow and outflow. The passage 22 has a branch 23 leading to one side of and opening into a recess 24 in the
60 body 8 extending from the top thereof, said body being provided with a gasoline or fuel supply passage 25 leading from the lower surface thereof between the casing 1 and tube 7 to the lower end of said recess 24. A
65 fuel conducting pipe or tube 26 extends lon-

gitudinally between the casing 1 and tube 7 and its upper end is secured in any suitable manner to the body 8 in communication with the passage 25, while the lower terminal of said pipe 26 extends outwardly through an insulating plug 27 in the wall of the cap 2, said terminal of the pipe 26 being connected by an insulating coupling 28 with the gasoline or fuel supply pipe 29 leading to the tank or other source of fuel. The insulation 70 prevents the grounding of the device at the points where not wanted. The gasoline or other fuel can thus flow from the supply pipe 29 into the vaporizing chamber by way of the pipe 26, passage 25, recess 24 and 80 passage 22.

The valve body 8 has a check valve for preventing the reverse flow of fluid in the fuel supplying conduit, a plug 30 being threaded or otherwise removably engaged 85 within the mouth of the recess 24 and a check valve 31 of conical or other suitable form being movable with said recess and having a stem 32 slidable within said plug to guide the valve to and from its seat 90 formed by the shoulder between the recess 24 and passage 25. A coiled expansion spring 33 is confined between valve 31 and plug 30 to seat said valve with a light ten-
95 sion. The check valve 31 therefore prevents reverse flow in the fuel conduit, and enables the fuel to flow readily to the vaporizing chamber.

The valve body 8 has a second check valve, and is therefore provided with a second 100 branch 34 leading from the passage 22 to the lower end of a second recess 35 extending from the top of the body 8. The body 8 has a vapor or gas outlet passage 36 leading from one side of the recess 35 to the lower 105 surface of said body between the casing 1 and tube 7, at which point a vapor or gas conducting pipe or tube 37 is secured to said body in communication with the passage 36. The pipe or tubing 37 is made of a suitable 110 metal, composition or alloy having a high specific electrical resistance, such as German silver, nickel, "nichrome" or other equivalent material, and is formed into a coil 38 surrounding the tube 7. The tubing is com-
115 paratively long and comparatively small in diameter, and being of metal such as de-
scribed, will be bendable or flexible, so that it can be bent into the coil or otherwise formed to suit conditions. The tubing will 120 therefore cause the stream therethrough to be quite long and of small cross section in order that the benefits of said tubing as a heater for the fluid will be derived. From the lower end of the coil 38, the pipe or tub-
125 ing 37 leads outwardly through an insulat-
ing plug 39 in the wall or flange of the cap 2 to be connected to the intake manifold or conduit 40 of the engine, preferably between the carburetor and cylinder. The manifold 130

40 of the engine 41 is supplied with carbureted air from the usual carburetor 42. A plug 43 similar to the plug 30 is engaged within the mouth of the recess 35, and the 5 second check valve 44 similar to the valve 31 has the upstanding stem 45 slideable in and guided by the plug 43. The valve 44 is seatable against the seat formed by the shoulder between the passage 34 and recess 35, and a 10 coiled expansion spring 46 is confined between the valve 44 and plug 43 to seat said valve. This spring 46 is of sufficient tension to resist the opening of the valve 44 under the greatest vacuum or negative pressure in 15 the intake manifold due to the suction created by the intake stroke of the pistons when the engine is running. This is essential to prevent the usual vacuum or suction in the intake manifold from extending into the 20 priming device under running conditions, which if it occurred would be apt to draw the gasoline from the pipe 29 through the primer.

The electrical circuit includes the storage 25 battery 47 or other source of electrical energy, from one pole of which a conductor or leader 48 extends to the binding post of the electrode 13; and a conductor or leader 49 is grounded to the manifold 40 and is connected to the other pole of the battery by a 30 switch 50 used to open and close the circuit. With automobiles having an electrical starter 52 for mechanically moving the movable parts, the switch 50 may be the same as 35 that one which is operated to close the circuit 51 of the starter. In this way, the primer will be heated instantly when the starter is brought into operation, causing the vapor or gas to flow to the intake manifold for the prompt response of the engine. 40 However, this is optional, and a separate circuit for the priming device can be used with or without a starting device for the engine.

45 When the device is first attached, gasoline or other fuel used is supplied within the vaporizing or retort chamber. This can be done when the device is manufactured, or in any other manner, such as by sucking the 50 fuel into said chamber by applying sufficient suction from a pump to the tubing 37 to overcome the resistance of the spring 46, whereupon the fuel will flow into the chamber as the air is withdrawn therefrom, by 55 the pumping action.

In operation, when the electrical circuit is closed by the switch 50, the electrical current flows through the device, said circuit including the conductor 48, electrode 13, carbon 60 pack 17, electrode 19, spring 21, valve body 8, tubing 37, manifold or other ground 40, and conductor 49. The flow of electrical energy through the carbon pack will heat the carbon particles and the tubing 37, 65 whereby the fuel which fills the interstices

of the carbon pack will be heated and therefore vaporized, and the vapor or gas being confined within the fluid-tight chamber will increase in pressure until the pressure overcomes the resistance of the spring 46, whereupon the vapor or gas will flow from the chamber through the tubing 37 to the engine intake. The resistances of the carbon pack and tubing 37 are such that the tubing will become hotter than the carbon pack, and 70 while the carbon pack dissipates sufficient heat to the fuel to vaporize it and force said vapor through the tubing 37, said tubing and its coil 38 will dissipate additional heat to the vapor flowing in said tubing, and the 75 vapor in absorbing heat from the tubing 37 and its coil will increase in temperature and become superheated, and since the tubing extends to the manifold, the vapor will be kept in this condition to the very point of 80 entering the manifold. The vapor when passing from the priming device to the manifold is thus surrounded by a heated conduit to maintain the temperature of the vapor 85 and prevent it from cooling or condensing 90 before mixing with the carbureted air, such condensing of the vapor in the manifold also being avoided due to the superheating thereof. The superheated vapor in mixing with the carbureted air raises the temperature of said air and gasoline mixed therewith, and the resultant mixture or charge is heated and will ignite easily and quickly, for the prompt starting of the engine, even when the atmospheric temperature is too 95 low to allow proper carburetion of the air when passing through the carburetor. Even though the carbureted air is cold, the superheated vapor supplied by the device will heat the air by giving up some of its heat 100 to the air, but retaining sufficient to avoid condensation. The check valve 31 prevents the vapor from flowing into the fuel conduit.

When the electrical circuit is opened, after the engine has started, the electrical current 110 will no longer flow in the vaporizing chamber, and the remaining vapor therein will therefore condense when the device cools, thus creating a partial vacuum in said chamber that extends into the fuel conduit and 115 draws fuel from said conduit past the valve 31 into said chamber, thereby replenishing the supply of fuel therein automatically for the next operation.

Figs. 2 and 3 depict a different form of 120 the device having the same principles of operation, showing one of many modifications which can be made. This modified form is designed to be placed in the intake conduit of the engine, such as between the 125 intake manifold and carburetor, and comprises a block or body 1' and bottom and top plates 2' and 9', respectively, between which said body is disposed. This body is provided with lower and upper grooves or 130

channels 7' and 7'', respectively extending in loop form around a central opening 40' in the body 1' to register with the intake conduit for the flow of carbureted air there-
5 through from the carbureter into the intake manifold, said body being readily clamped between the manifold and carbureter and held in place by the clamping bolts for the reception of which the body 1' has bolt holes 53. The grooves 7' and 7'' are covered by the plates 2' and 9', respectively, and are lined throughout, as at 11', with mica, asbestos or other heat and gasoline resisting insulation. The lower groove 7' provides
10 the vaporizing chamber or retort in which the fragments or pellets of carbon or like material are packed tightly, so that the pack surrounds the opening 40'. An electrode disk 18' is carried by the plate 2' within
15 one end of the groove or vaporizing chamber 7', and has a stem 14' extending outwardly through the plate 2', with nuts 14'' thereon for the connection of the conductor 48. The electrode 13' has the contact points 18' entering the carbon pack to make good electrical connection therewith. Insulation 15' surrounds the stem 14' to insulate the electrode 13' from the plate 2'. The body 1' has an opening 23', between the ends of the
20 chamber 7' as shown, and a coupling 28' of insulating material is fitted in the opening 23' and has the fuel supply pipe 29' connected thereto for delivering the fuel into the chamber 7' when the vapor in said chamber condenses. The coupling 28' contains the check valve of the fuel conduit, that end of the coupling 28' which opens into the chamber 7' having a recess 24' from which a restricted passage 25' leads to the pipe 29'.
25 The shoulder between the recess 24' and passage 25' forms a seat for the check valve 31' whose stem 32' is guided by a spider 30' within the recess 24', the valve being seated by an expansion spring 33' confined between
30 the valve and spider.
35 A cup 25' extends through a plate 9' into one end of the groove or dead air space 7'', and is insulated from said plate by insulation 55 between said cup and plate. The bottom of the cup has an extension 19' projecting through the partition between the chamber 7' and dead air space 7'', packing 54 surrounding the extension 19' within the opening in said partition to prevent leakage.
40 A nut 21' is threaded onto the extension 19' in the chamber 7' to clamp the cup 35' in place, and said extension has a passage 34' and a port or aperture 22' for the flow of vapor out of the chamber 7'. The extension 19' provides the second electrode within the other end of chamber 7' and said extension has radial contact points 20' entering the carbon pack to insure a good electrical connection. A plug 43' closes the mouth of the cup 35' and guides the stem 45' of a
45

check valve 44' for the vapor or gas conduit seatable against the bottom of the cup. A spring 46' seats the valve 44' with the desired pressure, like the spring 46 seats the valve 44.

The resistance and superheating tubing 37' is located within the groove or dead air space 7'' so as to be protected from the atmosphere, like the coil 38' is protected within the annular dead air space of the first 75 form between the tube 7 and casing or shell 1. The tubing 37' has a coil 38' extending within the space 7'' around the opening 40' and one or more of such coils can be used, as desired. One end of the tubing 37' is 80 attached to and communicates through the wall of the cup 35' to receive the vapor, while the other end of the tubing is engaged through the inner wall of the space 7'' and opens into the opening 40'', so that the 85 vapor discharged from said tubing intercepts the carbureted air flowing therethrough to admix therewith effectively.

The operation is substantially the same as above described, but briefly stated is as follows: The electrical current, when the circuit is closed, flows between the electrodes from one end of the carbon pack to the other, thereby vaporizing the fuel. The circuit from one electrode to the battery is 95 made by way of the conductor 48, and from the other electrode 19' by way of the cup 35', tubing 38' and body 1' grounded to the manifold by contact therewith. The expanding vapor flows through the passage 34' 100 past the valve 44' into the cup 35' and through the tubing 37' into the opening 40'. The tubing 37' thus superheats the vapor until it enters into the intake conduit. When the flow of electrical energy stops, 105 the vapor in chamber 7' condenses and produces a partial vacuum for drawing in more fuel for the next operation.

Various other modifications and alterations can be made within the scope of what 110 is now claimed, without departing from the spirit of the invention, to adapt the primer to various uses and conditions.

Having thus described the invention, what is claimed as new is:—

1. The combination with an internal combustion engine, of a fuel vaporizing chamber to confine a quantity of fuel and its vapor, having a fuel inlet and vapor outlet, a valve for admitting a quantity of fuel 120 through the inlet only when the chamber is not heated and to confine the fuel and vapor, and a conduit for conducting vapor under pressure from the vapor outlet to the engine intake.

2. The combination with an internal combustion engine, of a fuel vaporizing chamber to confine a quantity of fuel and its vapor, having a fuel inlet and a vapor outlet, a valve for admitting a quantity of fuel 130

- through the inlet and confine it in the chamber, a conduit connecting the vapor outlet and engine intake, and means for preventing the intake suction from drawing fuel or vapor from said chamber when it is not heated and vapor not produced. 5
3. The combination with an internal combustion engine and a source of fuel, of a fuel vaporizing chamber to confine a quantity of fuel and its vapor, having a fuel inlet communicating with the source of fuel, and a vapor outlet communicating with the engine intake, and means whereby fuel is admissible from the source of fuel through the fuel inlet before the chamber is heated and is confined as well as its vapor until the chamber is heated, and the vapor under pressure permitted to escape through the vapor outlet. 10
- 15 4. The combination with an internal combustion engine and a source of fuel, of a fuel vaporizing chamber to confine a quantity of fuel and its vapor, having a fuel inlet connected to said source of fuel, and a vapor outlet connected to the engine intake, a check valve for the fuel inlet to prevent reverse flow and to confine the fuel and its vapor in the chamber, and a check valve for the vapor outlet held seated with sufficient pressure to prevent the opening thereof by the intake suction unless assisted by the vapor when under pressure by the heating of the chamber. 20
- 25 5. A priming device embodying a vaporizing chamber having heating means for receiving and vaporizing a quantity of fuel and confining same and its vapor, said chamber having a fuel inlet and vapor outlet with means to confine the fuel and vapor and permitting the vapor, when under sufficient pressure, to pass out through the outlet. 30
- 35 6. In a heated fluid supplying device, a liquid vaporizer for holding fuel and vaporizing it, and a conduit arranged for only receiving vapor therefrom after being generated and composed of electrical conducting material having a high specific electrical resistance, to be disposed in an electrical circuit so that said conduit becomes heated for externally superheating the vapor during transit. 40
- 45 7. In a heated fluid supplying device, a liquid vaporizer for holding fuel having electrical resistance for heating it to vaporize the fuel, and a conduit arranged for only receiving vapor from said vaporizer after being generated and composed of electrical conducting material having a high specific electrical resistance and connected in electrical circuit with the resistance of the vaporizer to externally superheat the vapor during transit in the conduit during vaporization. 50
- 55 8. An engine primer having a vaporizing chamber, provided with a fuel inlet and a vapor outlet to discharge into an engine intake, a valve for the inlet, and a check valve for the outlet held closed with sufficient pressure to prevent the intake suction from extending into said chamber until assisted by vapor pressure therein. 70
- 60 9. An engine primer having a vaporizing chamber provided with a fuel inlet and a vapor outlet, means for heating said chamber at will, a check valve for the inlet, and a check valve for said outlet held seated with sufficient pressure to prevent the intake suction from extending into said chamber until assisted by vapor pressure therein. 75
- 65 10. An engine primer having a vaporizing chamber, means for the discharge of vapor therefrom to an engine intake, and means arranged for preventing the intake suction from entering said chamber but permitting the vapor to flow out to the intake when under pressure. 80
- 70 11. An engine primer having a vaporizing chamber provided with a fuel inlet and vapor outlet and electrical resistance, a conduit having high specific electrical resistance for conducting vapor from said outlet to an engine intake and electrically heating it, a check valve for the inlet, the electrical resistance of said chamber being in circuit with said conduit, and means for preventing the intake suction from extending through said conduit into said chamber but permitting the vapor to flow out to the intake when under pressure. 90
- 75 12. The combination with an engine, a carbureter therefor, and a starter for transmitting mechanical impulse to the engine for starting it, of priming means constructed and arranged for supplying confined vapor under pressure to the engine independent of said carbureter, means for bringing the priming means into operation for supplying confined vapor under pressure irrespective of the operation of the carbureter, 100 and means whereby the last named means is operated when the starter is operated. 105
- 80 13. The combination with an engine, a carbureter therefor, and an electrical starter for transmitting mechanical impulse to the engine for starting it, of priming means constructed and arranged for supplying confined vapor under pressure to the engine intake independent of the carbureter, electrical means for bringing the priming means 110 into operation, a source of electrical energy, and means operable for supplying energy simultaneously to the starter and said electrical means so that confined vapor under pressure flows to the engine intake when it receives the mechanical impulse from the starter. 115
- 85 14. The combination with an engine intake, of means constructed and arranged to receive and confine fuel and its vapor, to 120
- 90 125

heat said confined fuel at will, and to deliver the vapor thus formed, when under sufficient pressure only, to the intake.

15. The combination with an engine intake and means for supplying fuel; of means constructed and arranged to receive fuel from said means and confine it and its vapor, to heat the confined fuel at will, and to deliver the vapor thus formed, when under sufficient pressure only, to the intake.

16. The combination with an engine intake and means for supplying fuel; of means constructed and arranged to automatically receive fuel from said means when the second named means is cool and confine said fuel and its vapor, to heat the confined fuel at will, and to deliver the vapor thus formed, when under sufficient pressure only, to the intake.

20 17. The combination with an engine intake and means for supplying fuel; of a

vaporizing chamber; and means for conducting fuel from said means to the chamber and confining it therein, conducting vapor from the chamber to the intake, and preventing the flow of fuel or vapor past said chamber by the suction from the intake when vapor is not produced.

18. The combination with an engine intake and means for supplying fuel; of a vaporizing chamber; and means whereby when the chamber is cool, and vapor therein condensed, fuel is sucked thereinto from said means and the intake suction shut off from the chamber, and when the chamber is heated, vapor is delivered therefrom to the engine intake only when the vapor pressure rises to a predetermined amount.

In testimony whereof we hereunto set our hands and seals, this 22 day of Feb., 1918. 40

FREDERICK L. SHELOR.

FREDERICK C. SCHOFIELD.
